Primary Examiner — Ian Simmons*Assistant Examiner* — Wan Laymon(74) *Attorney, Agent, or Firm* — Workman Nydegger**CLAIM**

The ornamental design for a dental illumination device, as shown and described.

DESCRIPTION

FIG. 1 is a top perspective view of a dental illumination device according to the present invention;

FIG. 2 is a bottom perspective view of the dental illumination device;

FIG. 3 is a top view of the dental illumination device;

FIG. 4 is a side view of the dental illumination device;

FIG. 5 is a bottom view of the dental illumination device; and,

FIG. 6 is a front view of the dental illumination device. The dash-dot-dot line and the even dot line immediately adjacent to the shaded areas represent the bounds of the claimed design while all other dash-dot-dot lines are directed to environment and are for illustrative purposes only; none of the broken lines form part of the claimed design.
